UNITED STATES PATENT OFFICE.

SHERBURNE H. WIGHTMAN, OF BIRMINGHAM, MICHIGAN, ASSIGNOR, BY MESNE ASSIGNMENTS, TO INTERNATIONAL CONCRETE CORPORATION, OF WILMINGTON, DELAWARE, A CORPORATION OF DELAWARE.

CONCRETE MIXER.

Application filed July 14, 1920. Serial No. 396,104.

To all whom it may concern:

Be it known that I, SHERBURNE H. WIGHTMAN, residing at Birmingham, in the county of Oakland and State of Michigan, a citizen 5 of the United States, have invented or discovered, certain new and useful Improvements in Concrete Mixers, of which improvements the following is specification.

The invention described herein relates to 10 certain improvements for mixing materials employed in the formation of concrete, etc., and has for its object the provision of means whereby the materials are discharged into two adjacent troughs in the desired proportions and the materials thoroughly mixed 15 not only in each trough but the materials are also thrown back and forth from one trough to the other in such manner that the materials will be caused to mix and inter- 20 mingle in their passage from one trough to the other. The means employed for throwing the materials back and forth are so constructed and operated, that the paths of movement of the materials from the troughs 25 are not parallel but at an acute angle to the axes of the troughs, so that the paths of movement of the materials from the two troughs will intersect and the particles of materials will strike one against the other, 30 causing deflections from their original directions and a consequent thorough inter- mingling.

During the mixing operation the materials are advanced towards the discharge 35 end of the mixer, not only while in the troughs but also while being thrown from one trough to the other and finally forced in continuous streams from the troughs.

The initial mixing is effected while the 40 materials are dry, but water is supplied in suitable quantities during the mixing so that the material is discharged with the requisite water content, ready for use. The invention is hereinafter more fully described and 45 claimed.

In the accompanying drawings forming a part of this specification, Fig. 1 is a side elevation of the improved mixer; Fig. 2 is a front end elevation of the same; Fig. 3 is a 50 transverse section on a plane indicated by the line III—III, Fig. 1; Fig. 4 is a longitudinal section on a plane indicated by the line IV—IV, Fig. 2; and Fig. 5 is a rear end elevation.

In the practice of the invention the mixing chamber which has its front portion covered by the feed hopper as hereinafter described, while its rear portion may have its upper side open, has its bottom or floor so shaped as to form two closely adjacent troughs 1 and 2 extending by preference the entire length of the chamber. The troughs are preferably comparatively shallow so as to facilitate the movements of material from one trough to another. These troughs are 55 formed on arcs of circles having their centers coincident with the axes of shafts 3 and 4 which are mounted in bearings 5 and 6 formed respectively in the wall 7 closing the front end of the mixing chamber and 60 the yoke 8 extending across the rear end of the chamber and secured to the end frame of the chamber. On these shafts are secured a plurality of stirring paddles 9, the paddles being arranged on the respective shafts that 65 on the rotation of the latter the paddles on one shaft will pass between adjacent paddles on the other shaft. These paddles are 70 so constructed and arranged on their shafts that their operative faces will be comparatively broad so that when moving transversely of the troughs they will displace and carry up and over substantial quantities of the material and will also operate 75 to move the material longitudinally of the troughs and out through the open rear ends of the troughs. The shafts are rotated in 80 opposite directions and the direction of rotation is preferably such that the paddles will enter the troughs at points along the inner and adjacent sides of the troughs, move outwardly across the troughs forcing 85 portions of the material to the outer sides of the troughs. This movement of the materials across the troughs will cause a banking up of the same along the outer sides of the troughs so that when the paddles move up through the banked mass, they will carry 90 substantial quantities on their upper surfaces. The shafts are rotated at such speeds 95 that the combined action of gravity and centrifugal force will hold the greater part of the material on the paddles until the paddles pass beyond vertical planes passing 100 the axes of the shafts, when the material will leave the paddles with such momentum 105 that material carried from one trough will drop into the other trough and vice versa.

It will be observed that by reason of the inclination and curvature of the sides of the ridge intermediate the troughs, the materials will slide down towards the bottom of the troughs into the paths of movement of the paddles, and none of the materials can lodge outside of the field of action of the paddles.

It is characteristic of this method that there will be small masses of material lifted from each trough and thrown into the other trough, and in this movement passing through masses from the other trough. This operation ensures a thorough intermingling and mixture of the raw materials, bringing the cement into intimate contact with the said aggregate.

The paddles are formed of suitable material and are secured in pairs on the shafts, the members of each pair projecting in opposite directions. While the paddles may be secured to the shafts in any suitable manner, it is preferred that they should have their inner ends secured in sockets 10 formed on sleeves 11 removably secured on the shafts.

The materials are fed into the troughs preferably from a hopper 12 arranged above the front portion of the mixing chamber. This hopper is divided by a plurality of partitions 13 into compartments for the reception of the several materials to be mixed, and the hopper is provided with suitable means whereby the materials may be discharged from the respective compartments in the proportions desired in the finished mixture. A convenient construction for that purpose consists in supporting the materials in the compartments on a plate 14 movable transversely of the troughs in the mixing chamber. This plate is made of such a length that it can be so reciprocated back and forth that the end portion will extend alternately beyond the sides of the hopper distances proportional to the quantities of material to be fed into the troughs. This plate, while it may be supported in any suitable manner is preferably provided along its sides with ribs 15 which may be grooved as at 16 and bear upon the balls 17 arranged in a raceway. In order to reciprocate this plate, arms 18 are secured on a shaft 19, the outer ends of the arms being connected to the underside of the plate, as clearly shown in Figs. 3 and 4, and on the outer end of this shaft is a sleeve 19a loosely mounted on the shaft and adapted to be connected thereto by a clutch 20. This sleeve is provided with an arm 21, slotted adjacent to its outer end and adapted to be connected to an arm 22 on the strap 23 of the eccentric 24. This eccentric is secured on a countershaft 25 on which is loosely mounted a pinion 26 intermeshing with a pinion on one of the shafts carrying

the paddles. By the rotation of this countershaft, the shaft 19 will be oscillated back and forth imparting a reciprocatory movement to the plate 13, the amount of reciprocation being variable by the adjustment of the connection between the arm on the eccentric strap and the arm on the sleeve 20. This construction permits of the adjustment

of the rate of feed of materials relative to the rate of rotation of the mixing shafts and arms. As the plate is moved in the direction of the arrow *a* the material resting thereon will be carried outside of the hopper, the sides of which stop short of the plate and the thickness of the material will depend upon the distance between the lower edge of the side of the hopper from the surface of the plate. In order to regulate the amount of material thus carried from the hopper by the plate, the distance between the side of the hopper and the plate is made greater than would permit an amount ordinarily used to be mixed, and the gap thus made can be varied by means of sliding doors 27 mounted in guides on the sides of the hopper. The quantity of material fed to the troughs is also regulable by changing the range of movement of the plate 13.

After the plate carrying the material has reached the limit of its outward movement in one direction, it is shifted back in the reverse direction, but by reason of the mass of material in the hopper resting on the plate, that which has been carried out cannot be moved back into the hopper, but will drop into the trough as the plate is withdrawn. In other words, the material within the hopper serves as an abutment or stop to prevent the carrying back of any material by the movement of the plate. If desired, a plate or abutment 27a may be arranged in the hopper to prevent material moving back into the latter with the feed plate. The feed construction above described provides for the feed of material into both troughs.

It has been hereinbefore stated that the arms on the shafts move outwardly across the troughs and that by the action of the paddles or arms the materials are thrown from points adjacent to the outer walls of one trough into the opposite trough to insure a thorough mixing. Mixing is further insured by so feeding materials into the troughs, i. e., adjacent to the side walls of the respective troughs, that the materials will encounter the arms as they move upward carrying portions of material previously fed which together with the materials just dropping from the hopper, will be thrown from one trough to the other. This operation is clearly shown in Fig. 3.

As hereinbefore stated, the paddles serve to move the material along the hopper, and at a suitable point in the traverse of this material towards the discharge ends of the

troughs suitable means are employed for sprinkling water onto the mixed materials. In the construction shown, this means consists of a pipe 28 provided with a suitable 5 regulating valve and having laterally extending branches 29 perforated for the escape of water into the materials.

While not necessary, it is preferred that the sides 30 of the trough be formed of metal 10 plates hinged or pivotally connected along their edges to shafts 31 secured in the frames forming part of the mixing chamber and adapted to be held in closed position by means of sliding bolts 32. As will be seen 15 by reference to Fig. 3 these doors are hinged sides and extend down to practically the bottom of the troughs so that by raising the doors, the troughs may be thoroughly and easily cleaned of any material therein.

20 It is characteristic of the improved mixer that the materials are discharged into two troughs having open ends through which there will be continuous movements of the materials thoroughly mixed by the action of the paddles which also operate to stir the materials but also to throw them back and forth from one trough to the other thus ensuring that both streams are practically uniform as to mixture.

30 It will be observed that there is an interval between the discharge of materials into the troughs, but the materials in the troughs are moved continuously so that subsequent charges will not drop onto previously charged quantities.

I claim herein as my invention:

1. A mixing apparatus having in combination a mixing chamber having its bottom formed by troughs extending side by side, the end wall of the chamber having openings in line with the troughs for the discharge of materials, rotatable shafts arranged above said troughs and provided with arms adapted on the rotation of the shafts to pass transversely across the troughs in such direction that materials are moved outwardly across the troughs and over the shafts from one trough to the other and arranged to effect movement of materials along the troughs and out through the openings in the end of the mixing chamber, means for rotating the shafts in opposite directions and regulable means for feeding the material to the respective troughs.

2. A mixing apparatus having in combination a mixing chamber having its bottom formed of troughs extending side by side, the end wall of the chamber having openings in line with the troughs for the discharge of material, rotatable shafts arranged above said troughs and provided with arms adapted, on the rotation of the shafts, to pass transversely across the troughs and arranged to effect a movement

of the materials along and out through the openings in the end of the mixing chamber, means for rotating the shafts in opposite directions and means for feeding material to the troughs intermittently and alternately.

3. A mixing apparatus having in combination a mixing chamber having its bottom formed of troughs extending side by side, said chamber having openings in its end wall in line with the troughs for the discharge of materials, rotatable shafts arranged above said troughs and provided with arms adapted on the rotation of the shafts to pass transversely across the troughs and arranged to effect a movement of the materials along the troughs and out through the end of the chamber, means for rotating the shafts in opposite directions and means for feeding materials to be mixed into said troughs, alternately.

4. A mixing apparatus having in combination a mixing chamber having its bottom formed by troughs extending along side by side, said chamber having openings in its end wall in line with the troughs for the discharge of materials, rotatable shafts arranged above said troughs and provided with arms adapted on the rotation of the shafts to pass transversely across the troughs and arranged to effect movement of the materials along the troughs and out through the openings in the end of the chamber, means for so rotating the shafts that the portions of the arms passing through the material will move outwardly, and means for feeding material alternately into the respective troughs.

5. A mixing apparatus having in combination a mixing chamber having its bottom formed by troughs extending side by side beyond the end of the chamber, said chamber having openings in its end wall in line with the troughs for the discharge of material, rotatable shafts arranged above said troughs and provided with arms adapted to, on the rotation of the shafts, pass transversely across the troughs, means for so rotating the shafts that the arms will move outwardly when passing across the troughs, means for feeding material intermittently into the portion of said troughs within the chamber and means for feeding water to the materials subsequent to their being mixed by the operation of the arms.

6. A mixing apparatus having in combination a mixing chamber having its bottom formed by curved troughs extending side by side, said chamber having openings in its end in line with the troughs for the discharge of materials and removable side walls for said chamber, shafts arranged above the troughs with their axes coincident with the center of curvature of the troughs and provided with radially arranged arms adapt-

ed on the rotation of the shafts to move across the troughs and cause the material to move along the troughs and out through the openings in the chamber, means for rotating the shafts and means for the independent feeding of materials to each of the troughs.

7. A mixing apparatus having in combination a mixing chamber having its bottom formed by troughs extending side by side beyond the end of the chamber, said chamber having openings in its end in line with the troughs for the discharge of materials, shafts provided with arms adapted to move transversely across the troughs on the rotation of the shafts and effect movement of the materials along the troughs and out through the openings in the chamber, means for constantly rotating said shafts, means operative by the shafts for feeding materials intermittently into the respective troughs and means for supplying water to the materials after passing from the chamber.

25 8. A mixing apparatus having in combination a mixing chamber having its bottom formed of troughs extending side by side, said chamber having openings in its end wall in line with said troughs for the discharge of material, shafts provided with arms adapted to move transversely across the troughs on the rotation of the shafts to effect a movement of the materials along the troughs and out through the openings 35 from the chamber, means for rotating said shafts, a hopper provided with discharge openings one above each of said troughs in its side walls, a feed plate forming the bottom of the hopper and adapted to be reciprocated to carry material out through the discharge openings and into said troughs alternately and means operative by said shafts for reciprocating the feed plate.

9. A mixing apparatus having in combination a mixing chamber having its bottom formed of troughs extending side by side, said chamber having openings in its ends wall in line with the troughs for the discharge of materials, shafts provided with 45 arms adapted to move transversely across the troughs on the rotation of the shafts and effect a movement of the materials

along the troughs and out through the openings from the chamber, means for rotating said shafts, a hopper provided with discharge openings in its side walls, a feed plate forming the bottom of the hopper and adapted when shifted to carry material out through the discharge openings, means for reciprocating the feed plate and an abutment in the hopper adapted to prevent material from being moved back into the hopper by the plate.

10. A mixing apparatus having in combination a mixing chamber having its bottom formed by troughs, extending side by side, said chamber having openings in its end wall in line with the troughs for the discharge of material, rotatable shafts arranged above said troughs and provided with arms adapted on the rotation of the shafts to pass transversely across the troughs, means for rotating the shafts, a hopper, means for feeding material from the hopper into the troughs, and adjustable connections from the feeding means to the shafts.

11. A mixing apparatus having in combination troughs extending side by side, rotatable shafts arranged above said troughs and provided with arms adapted on the rotation of the shafts to pass transversely across the troughs, means for so rotating the shafts that the arms will move outwardly when passing across the troughs and means for feeding materials to the troughs intermediate the shafts and the outer walls of the respective troughs.

12. A mixing apparatus having in combination troughs extending side by side, rotatable shafts arranged above said troughs, and provided with arms adapted on the rotation of the shafts to pass transversely across the troughs, means for so rotating the shafts that the arms will move outwardly when passing across the troughs and means for alternately feeding materials into the troughs in such manner that the materials will encounter the arms during their upward movements.

In testimony whereof, I have hereunto set my hand.

SHERBURNE H. WIGHTMAN.
